SYNTHETIC CEPHALOSPORINS

William Joseph Gottstein, Fayetteville, and Ann Hallstrand Eachus, Syracuse, N.Y., assignors to Bristol-Myers Company, New York, N.Y., a corporation of Delaware
 No Drawing. Filed July 7, 1966, Ser. No. 563,355
 16 Claims. (Cl. 260—243)

This invention relates to new synthetic compounds of value as antibacterial agents, as nutritional supplements in animal feeds, as agents for the treatment of mastitis in cattle, and as therapeutic agents in poultry and animals, including man, in the treatment of infectious diseases caused by Gram-positive and Gram-negative bacteria and, more particularly, relates to certain 7-[N,N-disubstituted-carbamoyl (and thiocarbamoyl)-mercapto-acetamido]cephalosporanic acid and related salts and derivatives.

Antibacterial agents in the past have proven highly effective in the therapy of infections due to either Gram-positive or Gram-negative bacteria but few are effective against both. It was the objective of the present invention to provide novel compounds effective against both Gram-positive and Gram-negative bacteria including the resistant strains. It was a further object of the present invention to provide cephalosporins active against Gram-positive and Gram-negative bacteria which are also efficiently absorbed upon parenteral or oral administration to man and animals.

The objects of the present invention have been achieved by the provision, according to the present invention, of the compounds of the formula

wherein X is oxygen or sulfur, B is a secondary amino group; A is hydrogen, hydroxyl, (lower) alkanoyloxy containing 2-8 carbon atoms, e.g., acetoxy, propionyloxy, butanoxyloxy, pentanoyloxy, etc. benzoyloxy, a quaternary ammonium radical, e.g. pyridinium, quinolinium, picolinium, lutidinium, or, when taken together with M, a monovalent carbon-oxygen bond; and M is hydrogen, a pharmaceutically acceptable nontoxic cation, an anionic charge when A is the quaternary ammonium radical, or, when taken together with A, a monovalent carbon-oxygen bond.

The term "(lower)alkyl" as used herein means both straight and branched chain aliphatic hydrocarbon radicals having from 1 to 6 carbon atoms such as methyl, 55 ethyl, propyl, isopropyl, butyl, isobutyl, t-butyl, amyl, hexyl, etc. Similarly, where the term "(lower)" is used as part of the description of another group e.g. "(lower) alkoxy," it refers to the alkyl portion of such group which is therefore as described above in connection with "(lower)alkyl" and thus includes such radicals as methoxy, ethoxy, isopropoxy, etc.

In addition to the secondary amino groups in which two bonds of the nitrogen atom form part of a nonaromatic carbocyclic or heterocyclic ring, the term secondary amino group includes, but is not limited to, groups of the formula

70

in which each of A and B represents a radical selected from the following list:

(1) Aliphatic radicals, for example:

Alkyl radicals, e.g.:

Methyl

Ethyl

Propyl (n- and iso-)

Butyl (n-, sec-, iso-, and tert-)

Amyl (n-, sec-, iso-, and tert-)

Hexyl radicals, e.g.:

n-Hexyl

Sec-hexyl

2,2-dimethyl-3-butyl

2,2-dimethyl-4-butyl

2,3-dimethyl-2-butyl

2-methyl-1-pentyl

2-methyl-2-pentyl

3-methyl-1-pentyl

3-methyl-2-pentyl, etc.

Heptyl radicals, e.g.:

n-Heptyl

Sec-heptyl

2,3-dimethyl-3-pentyl

2,4-dimethyl-2-pentyl

2,4-dimethyl-3-pentyl

2,2,3-trimethyl-3-butyl

3-ethyl-2-pentyl

2-methyl-2-hexyl, etc.

Octyl radicals, e.g.:

n-Octyl

2-ethyl-hexyl

Diisobutyl

Capryl

Nonyl radicals, e.g.:

Di-isobutyl-carbinyl

n-Nonyl

Decyl radicals, e.g. n-decyl

Dodecyl radicals, e.g. lauryl

Tetradecyl radicals, e.g. myristyl

Hexadecyl radicals, e.g. cetyl

Octadecyl radicals, e.g. stearyl

Alkenyl radicals, e.g.:

Vinyl

Propenyl radicals, e.g.:

Allyl

Isopropenyl

Butenyl radicals, e.g.:

n-Butenyl-1

n-Butenyl-2

n-Butenyl-3

Isobutenyl

Pentenyl radicals, e.g.:

n-Pentenyl-1

n-Pentenyl-2

n-Pentenyl-3

Hexenyl radicals, e.g.:

n-Hexenyl-1

n-Hexenyl-2, etc.

4,4-dimethyl-butenyl-2

3,4-dimethyl-butenyl-1, etc.

Heptenyl radicals, e.g. n-heptenyl

Octenyl radicals, e.g.:

n-Octenyl

Diisobutyl

Nonenyl radicals, e.g. n-nonenyl

Decenyl radicals, e.g. n-decenyl

Dodecenyl radicals, e.g.:

n-Dodecenyl

triisobutyl

Alkenyl radicals having the formula C_nH_{2n-1} where n is an integer from 18 to 38 inclusive,

e.g. those derived from paraffin wax, mineral oils, and petrolatum.	
(2) Cycloaliphatic radicals, for example:	
Cycloalkyl radicals, e.g.:	
Cyclopentyl, alkylated-cyclopentyl, cyclohexyl, and alkylated-cyclohexyl radicals, e.g.:	5
Mono- and poly-methyl-cyclopentyl radicals	
Mono- and poly-methyl-cyclohexyl radicals	
Mono- and poly-ethyl-cyclohexyl radicals	10
Mono- and poly-isopropyl-cyclohexyl radicals	
Mono- and poly-tert-amyl-cyclohexyl radicals	15
n-Octyl-cyclohexyl radicals	
Diisobutyl-cyclohexyl (i.e. "tert-octyl"-cyclohexyl) radicals	
Nonyl-cyclohexyl radicals	
Diiso-amyl-cyclohexyl radicals	20
Lauryl-cyclohexyl radicals	
Cetyl-cyclohexyl radicals	
Naphthenyl radicals	
Hydroabietyl radicals	
Cycloalkenyl radicals, e.g.:	25
Cyclopentenyl, alkylated-cyclopentenyl, cyclohexenyl, and alkylated-cyclohexenyl radicals, e.g.:	
Mono- and poly-methyl-cyclopentenyl radicals	
Mono- and poly-methyl-cyclohexenyl radicals	30
Mono- and poly-ethyl-cyclohexenyl radicals	
Mono- and poly-isopropyl-cyclohexenyl radicals	35
Mono- and poly - tert - amyl-cyclohexenyl radicals	
n-Octyl-cyclohexenyl radicals	
Diisobutyl-cyclohexenyl radicals	40
Nonyl-cyclohexenyl radicals	
Diiso-amyl-cyclohexenyl radicals	
Lauryl-cyclohexenyl radicals	
Cetyl-cyclohexenyl radicals	
Dehydronaphthenyl radicals	45
Abietyl radicals	
(3) Aryl- and cycloalkyl-substituted aliphatic radicals, for example:	
(a) Phenyl- and alkyl-phenyl-substituted alkyl radicals, e.g.:	
Benzyl	50
Methyl-benzyl	
Capryl-benzyl	
Diisobutyl-benzyl	
Phenyl-ethyl	55
Phenyl-propyl	
Phenyl-octadecyl	
(b) Xenyl- and alkyl-xenyl-substituted alkyl radicals, e.g.:	
Xenyl-methyl	60
Capryl-xenyl-methyl	
Xenyl-ethyl	
Diisobutyl-xenyl-methyl	
(c) Naphthyl- and alkyl-naphthyl-substituted alkyl radicals, e.g.:	65
Naphthyl-methyl	
Tert-amyl-naphthyl-methyl	
Naphthyl-ethyl	
Cetyl-naphthyl-ethyl	
(d) Cyclohexyl- and alkyl-cyclohexyl-substituted alkyl radicals, e.g.:	70
Cyclohexyl-ethyl	
Methyl-cyclohexyl-ethyl	
Ethyl-cyclohexyl-ethyl	
Cyclohexyl-propyl	75

Tert-amyl-cyclohexyl-butyl	
(4) Oxygen containing aliphatic and cycloaliphatic radicals, for example:	
(a) Oxygen-containing aliphatic radicals, e.g.:	
Alkoxy-substituted alkyl radicals, e.g.:	
Propoxy-ethyl radicals, e.g.:	
n-Propoxy-ethyl	
Iso-propoxy-ethyl	
Butoxy-ethyl radicals, e.g.:	
n-Butoxy-ethyl	
Iso-butoxy-ethyl	
Tert-butoxy-ethyl	
Octoxy-ethyl radicals, e.g.:	
n-Octoxy-ethyl	
Diisobutoxy-ethyl	
Di-butoxy-propyl radicals, e.g.:	
2,3-di-n-butoxy-propyl	
3,3-di-iso-butoxy-propyl	
Di-octoxy-propyl radicals, e.g.:	
3,3-di-n-octoxy-propyl	
2,3-bis-(diisobutoxy)propyl	
Cycloalkoxy-substituted alkyl radicals, e.g.:	
Cyclohexoxy-methyl	
Cyclohexoxy-ethyl radicals, e.g.:	
Beta-cyclohexoxy-ethyl	
Alpha-cyclohexoxy-ethyl	
Cyclohexoxy-butyl radicals, e.g.:	
2-(cyclohexoxy)-butyl	
2,3-di-cyclohexoxy-butyl	
Methyl-cyclohexoxy-propyl radicals, e.g.:	
2-(o-methyl-cyclohexoxy)-propyl	
2-(p-methyl-cyclohexoxy)-propyl	
Butyl-cyclohexoxy-ethyl radicals, e.g.:	
Beta-(p-tert-butyl-cyclohexoxy)-ethyl	
Alpha-(o-sec-butyl-cyclohexoxy)-ethyl	
Cyclopentoxy-ethyl radicals, e.g.:	
Alpha-cyclopentoxy-ethyl	
Beta-cyclopentoxy-ethyl	
Propyl-cyclopentoxy-methyl radicals, e.g.:	
Iso-propyl-cyclopentoxy-methyl radicals	
n-Propyl-cyclopentoxy-methyl radicals	
Alkenoxy-substituted alkyl radicals, e.g.:	
Propenoxy-ethyl radicals, e.g.:	
Allyloxy-ethyl	
Iso-propenoxy-ethyl	
Octenoxy-ethyl radicals, e.g. diisobutenoxy-ethyl	
Di-octenoxy-propyl radicals, e.g. 2,3-bis-(diisobutenoxy)-propyl	
Aroxy substituted alkyl radicals, for example, phenoxy- and alkyl-phenoxy-substituted alkyl radicals, e.g.:	
Phenoxy-methyl	
Phenoxy-ethyl	
Cetyl-phenoxy-ethyl	
Phenoxy-phenethyl	
Capryl-phenoxy-phenethyl	
(b) Oxygen-containing cycloaliphatic radicals, e.g.:	
Alkoxy-, alkenoxy-, and aroxy-substituted cycloalkyl radicals, e.g.:	
Alkoxy - substituted cyclopentyl radicals, e.g.:	
Mono- and poly-ethoxy-cyclopentyl	
Octoxy-cyclopentyl radicals, e.g. disso-butoxy-cyclopentyl	
Alkoxy-substituted cyclohexyl radicals, e.g.:	
Mono- and poly-methoxy-cyclohexyl	
Octoxy-cyclohexyl radicals, e.g. diisobutoxy-cyclohexyl	
Alkenoxy-substituted cyclopentyl radicals, e.g.:	
Propenoxy-cyclopentyl radicals, e.g.:	
Allyloxy-cyclopentyl	

Iso-propenoxy-cyclopentyl	5
Alkenoxy-substituted cyclohexyl radicals, e.g.:	
Vinyloxy-cyclohexyl	
Propenoxy-cyclohexyl radicals, e.g.:	5
Allyloxy-cyclohexyl	
Iso-propanoxy-cyclohexyl	
Octenoxy-cyclohexyl radicals, e.g. di-isobutoxy-cyclohexyl	10
Aroxy-substituted cyclopentenyl radicals, e.g.:	
Phenoxy-cyclopentyl	
Poly - phenoxy - cyclopentyl radicals, e.g.:	15
Di-phenoxy-cyclopentyl radicals	
Ethyl - phenoxy - cyclopentyl radicals, e.g.:	20
o-Ethyl-phenoxy-cyclopentyl	
p-Ethyl-phenoxy-cyclopentyl	
Naphthoxy-cyclopentyl	25
Amyl-naphthoxy-cyclopentyl radicals, e.g.:	
Tert-amyl-alpha-naphthoxy-cyclopentyl radicals	
n - Amyl - beta - naphthoxy - cyclopentyl radicals	30
Aroxy-substituted cyclohexyl radicals, e.g.:	
Phenoxy-cyclohexyl	
Poly-phenoxy-cyclohexyl radicals, e.g.:	35
Di-phenoxy-cyclohexyl radicals	
Butyl-phenoxy-cyclohexyl radicals, e.g.:	
p-Tert-butyl-phenoxy-cyclohexyl	
n-Butyl-phenoxy-cyclohexyl	40
Naphthoxy-cyclohexyl radicals, e.g.:	
Alpha-naphthoxy-cyclohexyl	
Beta-naphthoxy-cyclohexyl	45
Methyl-naphthoxy-cyclohexyl radicals	
Propyl-naphthoxy-cyclohexyl radicals, e.g.:	
Iso-propyl-alpha-naphthoxy-cyclohexyl radicals	
n-Propyl-beta-naphthoxy-cyclohexyl radicals	50
(5) Aliphatic and cycloaliphatic radicals containing halogens. Examples of such radicals are:	
(a) Aliphatic radicals containing halogens, for example:	
Alkyl radicals containing halogen, e.g.:	
2-fluoro-ethyl	55
2-chloro-ethyl	
2-iodo-ethyl	
Chloro-pentyl radicals, e.g.:	
5-chloro-n-pentyl	
3,5-di-chloro-n-pentyl	55
Bromo-octyl radicals, e.g.:	
3-bromo-n-octyl	
3,4-di-bromo-n-octyl	
Alkenyl radicals containing halogen, e.g.:	
Chloropropenyl radicals, e.g.:	60
2-chloro-allyl	
chloro-iso-propenyl	
Bromo-butenyl radicals, e.g.:	
4-bromo-crotyl	
4,4-di-bromo-crotyl	
Chloro-octenyl radicals, e.g.: mono- and poly-chloro-diiso-butyl	65
(b) Cycloaliphatic radicals containing halogens, for example:	
Mono- and poly-chloro-cyclopentyl	70
Mono- and poly-chloro-methyl-cyclohexyl	
4-tert-amyl-2,6-di-bromo-cyclohexyl	
4-capryl-2-fluoro-cyclohexyl	
4-diisobutyl-2-iodo-cyclohexyl	
Mono- and poly-chloro-cyclopentenyl	75

Mono- and poly-chloro-methyl-cyclohexenyl	
4-tert-butyl-2-bromo-cyclohexenyl	
4-capryl-2-fluoro-cyclohexenyl	
4-diisobutyl-2-iodo-cyclohexenyl	
(6) Aromatic radicals, including aryl radicals, unsubstituted and substituted, including mono- and poly-alkylated and cycloalkylated aromatic nuclei, e.g.:	
Phenyl	
Cresyl	
Xylyl	
Mesityl	
Ethyl-phenyl	
Di-ethyl-phenyl	
Iso-propyl-phenyl	
n-propyl-phenyl	
Tert-butyl-phenyl	
Di-tert-butyl-phenyl	
Iso-butyl-phenyl	
n-Butyl-phenyl	
Tert-amyl-phenyl	
Cyclohexyl-phenyl	
Methyl-cyclohexyl-phenyl	
Capryl-phenyl	
Diisobutyl-phenyl	
Lauryl-phenyl	
Cetyl-phenyl	
Nitro-phenyl	
Mono-chloro-phenyl	
Poly - chl - o - phenyl, e.g. dichloro - phenyl, tri-chloro-phenyl	
Hydroxy phenyl	
Acetyl-phenyl	
Carbolauroxy-phenyl	
Lauroxy-phenyl	
Xenyl	
Mono- and poly-chloro-xenyl	
Capryl-xenyl	
Phenoxy-phenyl	
Thiophenoxy-phenyl	
Diisobutyl-phenoxy-phenyl	
Naphthyl	
Mono- and poly-chloro-naphthyl	
Cetyl-naphthyl	
Anthracyl	
Mono- and polychloranthracyl	
Phenanthryl	
Mono- and poly-chloro-phenanthryl	
Laurylphenanthryl	
(7) Aromatic radicals having more than one kind of substituent, e.g.:	
Alkyl-hydroxy-aryl radicals, e.g.:	
Mono-methyl-hydroxy-phenyl radicals	
Poly-methyl-hydroxy-phenyl radicals, e.g.:	
Di-methyl-hydroxyl-phenyl radicals	
Tri-methyl-hydroxy-phenyl radicals	
Mono-ethyl-hydroxy-phenyl radicals	
Poly-ethyl-hydroxy-phenyl radicals, e.g.:	
Di-ethyl-hydroxy-phenyl radicals	
Tri-ethyl-hydroxy-phenyl radicals	
Mono-butyl-hydroxy-phenyl radicals, e.g.:	
Tert-butyl hydroxy-phenyl radicals	
Sec-butyl-hydroxy-phenyl radicals	
Poly-butyl-hydroxy-phenyl radicals, e.g.:	
di-tert-butyl-hydroxy-phenyl radicals	
Mono-methyl-dihydroxy-phenyl radicals	
Poly-methyl-dihydroxy-phenyl radicals, e.g.:	
Di-methyl-dihydroxy-phenyl radicals	
Tri-methyl-dihydroxy-phenyl radicals	
Mono-propyl - hydroxy - naphthyl radicals, e.g.:	
mono-iso-propyl-alpha-hydroxy-naphthyl radicals	
Poly-propyl-hydroxy-naphthyl radicals, e.g.: di-n-propyl-beta-hydroxy-naphthyl radicals	
Alkyl-chloro-aryl radicals, e.g.:	
Methyl-monochloro-phenyl radicals	

Methyl-polychloro-phenyl radicals, e.g.:

Methyl-dichloro-phenyl radicals

Methyl-trichloro-phenyl radicals

Ethyl-monochloro-anthracyl radicals, e.g.:

Ethyl - monochloro - alpha - anthracyl
radicals

Triethyl - monochloro - beta-anthracyl
radicals

Ethyl-polychloro-anthracyl radicals, e.g.:

Ethyl-dichloro-alpha-anthracyl radicals

Diethyl-trichloro-beta - anthracyl
radicals

Alkyl-nitro-aryl radicals, e.g.:

Methyl-nitro-phenyl radicals

Dimethyl-nitro-phenyl radicals

Ethyl-dinitro-phenyl radicals

Butyl-nitro-naphthyl radicals, e.g.:

Tert-butyl-nitro-naphthyl radicals

Sec - butyl - dinitro-naphthyl
radicals

Propyl-nitro-phenanthryl radicals, e.g.:

Isopropyl - dinitro - phenanthryl
radicals

Di-n-propyl-dinitro - phenanthryl
radicals

Of those set out above, the preferred secondary amino groups are those having a molecular weight of less than 300.

For clarity, we have illustrated below the formulae of the compounds when, in Formula I, X is oxygen, B is diethylamino, A is a quaternary ammonium radical (pyridinium) and M is an anionic charge, and when A and M together are a monovalent carbon-oxygen bond.

A preferred group of compounds within the present invention is the group having the formula

wherein X is oxygen or sulfur; B is a secondary amino group, said secondary amino group containing in addition to its single nitrogen atom solely the elements carbon and hydrogen; A is hydrogen, hydroxyl, (lower)alkanoyloxy, benzoxyloxy, a quaternary ammonium radical or, when taken together with M, a monovalent carbon-oxygen bond; and M is hydrogen, a pharmaceutically acceptable nontoxic cation, an anionic charge when A is a quaternary ammonium radical or, when taken together with A, a monovalent carbon-oxygen bond.

Another preferred group of compounds within the present invention is the group having the formula

wherein X is oxygen or sulphur; B represents di(lower)-alkylamino wherein the alkyl group may be alike or different, piperidino, methyl-piperidino, dimethylpiperidino, pyrrolidino, methylpyrrolidino, dimethylpyrrolidino, morpholino, methylmorpholino, dimethylmorpholino, N'-(lower)alkylpiperazino, N' - (lower)alkylmethylpiperazino, N'-(lower)alkyl-dimethylpiperazino, trimethyleneimino, hexamethyleneimino or a radical of the formula

wherein n is zero, one, two or three, R is (lower)alkyl and Ar is a radical of the formula

or

wherein R¹ and R² are each hydrogen, fluoro, chloro, bromo, (lower)alkyl or (lower)alkoxy; A is hydrogen, hydroxyl, (lower)alkanoyloxy, benzoxyloxy, a quaternary ammonium radical or, when taken together with M, a monovalent carbon-oxygen bond; and M is hydrogen, a pharmaceutically acceptable nontoxic cation, an anionic charge when A is a quaternary ammonium radical or, when taken together with A, a monovalent carbon-oxygen bond.

The most preferred embodiments of the present invention are the free acids and salts thereof of which the free acids have the formulae

and

wherein R⁷ and R⁸ each represent hydrogen or methyl, X is sulfur or, preferably, oxygen; and B is a secondary amino group and preferably di(lower)alkylamino, piperidino, pyrrolidino, morpholino or N'-(lower)alkylpiperazino.

The pharmaceutically-acceptable, nontoxic cations include metallic cations such as sodium, potassium, calcium and aluminum and organic amine cations such as trialkylamines, e.g. triethylamine, procaine, dibenzylamine, N-benzyl - β - phenethylamine, 1 - ephenamine, N,N'-dibenzylethylenediamine, dehydroabietylamine, N,N'-bis-dehydroabietyleneethylenediamine, N - (lower)alkylpiperidines, e.g. N-ethylpiperidine, and other amines which have been used to form salts with benzylpenicillin.

The products of the present invention wherein X of Formula I is sulfur are prepared by the reaction of a compound of the formula

(VI)

wherein A and M are described above (preferably in the form of a neutral salt such as the sodium salt or the triethylamine salt, i.e. when A is hydrogen, hydroxy, (lower) alkanoyloxy or benzyloxy) with an acid having the formula

(in which B has the meaning set forth above) or with its functional equivalent as an acylating agent for a primary amino group. The preferred reagent is the mixed anhydride prepared by reacting such an acid with isovaleryl chloride (or pivaloyl chloride) in the presence of a tertiary amine such as triethylamine as an acceptor of hydrogen chloride. Such equivalents include the corresponding carboxylic chlorides, bromides, acid anhydrides, including mixed anhydrides and particularly the mixed anhydrides prepared from stronger acids such as the lower aliphatic monoesters of carbonic acid, of alkyl and aryl sulfonic acids and of more hindered acids such as diphenylacetic acid and isovaleric acid. In addition, an acid azide or an active ester or thioester (e.g. with p-nitrophenol, 2,4-dinitrophenol, thiophenol, thioacetic acid) may be used or the free acid itself may be coupled with 7-aminocephalosporanic acid after first reacting said free acid with N,N'-dimethylchloroformimidinium chloride [cf. Great Britain 1,008,170 and Novak and Weichert, Experientia XXI/6, 360 (1965)] or by the use of enzymes or of an N,N' - carbonyldiimidazole or an N,N' - carbonylditriazole [cf. South African Patent Specification 63/2684] of a carbodiimide reagent [especially N,N'-dicyclohexylcarbodiimide, N,N'-diisopropylcarbodiimide or N-cyclohexyl-N'-(2-morpholinethyl)carbodiimide; cf. Sheehan and Hess, J. Amer. Chem. Soc. 77, 1067, (1955)], or of alkynylamine reagent [cf. R. Buijle and H. G. Viehe, Angew. Chem. International Edition 3, 582 (1964)], or of a ketenimine reagent [cf. C. L. Stevens and M. E. Monk, J. Amer. Chem. Soc. 80, 4065 (1958)] or of an isoxazolium salt reagent [cf. R. B. Woodward, R. A. Olofson and H. Mayer, J. Amer. Chem. Soc. 83, 1010 (1961)]. Another equivalent of the acid chloride is a corresponding azolide, i.e. an amide of the corresponding acid whose amide nitrogen is a member of a quasi-aromatic five-membered ring containing at least two nitrogen atoms, i.e. imidazole, pyrazole, the triazoles, benzimidazole, benzotriazole and their substituted derivatives. As an example of the general method for the preparation of an azolide, N,N'-carbonyldiimidazole is reacted with a carboxylic acid in equimolar proportions at room temperature in tetrahydrofuran, chloroform, dimethylformamide or a similar inert solvent to form the carboxylic acid imidazolide in practically quantitative yield with liberation of carbon dioxide and one mole of imidazole. Dicarboxylic acids yield diimidazolides. The by-product, imidazole, precipitates and may be separated and the imidazolide isolated, but this is not essential. The methods for carrying out these reactions to produce a cephalosporin and the methods used to isolate the cephalosporin so-produced are well-known in the art (cf. U.S. Patents Nos. 3,079,314, 3,117,126 and 3,129,224 and British Patents Nos. 932,644, 957,570 and 959,054).

The compounds of Formula VI used in the present invention include 7-aminocephalosporanic acid and derivatives of 7-aminocephalosporanic acid. 7-aminocephalo-

5

sporanic acid is prepared by hydrolysis of cephalosporin C and has the formula

10 Acid hydrolysis of cephalosporin C to produce 7-aminocephalosporanic acid results in the coproduction of the lactone, 3-hydroxymethyl-7-aminodecephalosporanic acid lactone, formed by the further hydrolysis of the acetoxy group and subsequent internal esterification. The lactone has the formula

15 Enzymatic hydrolysis of the acetoxy group of 7-aminocephalosporanic acid results in the formation of 3-hydroxymethyl - 7 - aminodecephalosporanic acid having the formula

20 and such compound may be re-esterified with benzoic acid or a lower alkanic acid, e.g. acetic acid, propionic acid and the like to form other esters. Preferably, re-esterification is carried out on a 3-hydroxymethyl-7-(α -hydroxythienylacetamido)decephalosporanic acid which is obtained by enzymatic hydrolysis of a 7-(α -hydroxy-thienylacetamido)cephalosporanic acid.

25 Treatment of cephalosporin C with a tertiary amine, e.g. pyridine, lutidines, picolines and the like, followed by acid hydrolysis produces a nucleus which, in the case of pyridine, has the formula

30 and has been given the name 3-pyridiniummethyl-7-aminocephalosporanic acid inner salt.

35 The foregoing nuclei and the preparation thereof are known in the art and are described for example in U.S. Patent No. 3,117,126 and British Patents Nos. 932,644, 957,570 and 959,054.

40 3-methyl-7-aminodecephalosporanic acid having the formula

45 is produced by catalytic reduction of cephalosporin C followed by hydrolytic removal of the 5-aminoacetyl side chain as described in U.S. Patent No. 3,129,224.

50 There is thus provided by the present invention a

70

11

method for preparing antibiotic compounds having the general formula

wherein X is oxygen or sulfur; B is a secondary amino group;

wherein R⁴, taken alone, is —OH, C₁—C₈ acyloxy or tertiary-amino, R⁵ is —OH when R⁴ is —OH;

R⁵ is —OH when R⁴ is C₁—C₈ acyloxy; R⁵ is —O[⊖] when R⁴ is tertiary-amino;

R⁴ and R⁵ when taken together are —O—;

which comprises acylating a compound having the bicyclic ring structure of cephalosporin C and having a general formula represented by one of

where R⁶ is —OH or a C₁—C₈ acyloxy group and

wherein Am[⊕] is a tertiary-amino group; with an acylating agent having at least one constituent radical of the general formula

in which B and X have the meaning set forth above.

There is further provided by the present invention a method according to claim 15 for preparing antibiotic compounds having the general formula

wherein X is oxygen or sulfur; B is a secondary amino group;

wherein R⁴, taken alone, is —OH, C₁—C₈ acyloxy or tertiary-amino, R⁵ is —OH when R⁴ is —OH;

R⁵ is —OH when R⁴ is C₁—C₈ acyloxy; R⁵ is —O[⊖] when R⁴ is tertiary-amino;

R⁴ and R⁵ when taken together are —O—;

which comprises acylating a compound having the bicyclic

ring structure of cephalosporin C and having a general formula represented by one of

wherein R⁶ is —OH or a C₁—C₈ acyloxy group and

wherein Am[⊕] is a tertiary-amino group; with an acylating agent having at least one constituent radical of the general formula

wherein B and X have the meaning set forth above; and

(a) Heating the product with acidified water to form the corresponding acylated derivative of the nuclei of cephalosporin C_c compounds, or

30 (b) Refluxing the product in solution with an excess of a tertiary amine corresponding to Am[⊕] to form the corresponding acylated derivative of the nuclei of cephalosporin C_A compounds, or

(c) Treating the product with citrus acetyl esterase in a buffered aqueous medium to form the corresponding N-acylated derivative of the nuclei of desacetylcephalosporin C compounds.

There is also provided by the present invention a method for preparing nontoxic derivatives of the compounds produced by the methods set out above which comprises combining said products with pharmaceutically acceptable cations, anions, alcohols, ammonia or amines.

The products of the present invention wherein X of Formula I is oxygen are prepared in similar fashion by the use of an acid of the formula

(in which B has the meaning set forth above) or its functional equivalent as an acylating agent for a primary amino group. This is not the preferred method, however, as the acids of the formula

55 are not quite as easily prepared when X is oxygen as they are when X is sulfur.

A very effective and most unexpected method for producing the compounds of Formula I wherein X is oxygen is the process provided by the present invention of reaction of a compound of Formula IV directly with an acid of the formula

65 (wherein B has the meaning defined above; note that a sulfur atom occupies the position of the oxygen atom in the final product) in the presence of a mixture of iodine and an inorganic and preferably water-soluble iodide such as potassium iodide. The reaction is preferably carried out in a solvent (water is quite suitable) at about room temperature, although cooling or heating will merely slow or speed the reaction within reasonable limits, e.g. about 0°—50° C. The iodide/sodium iodide solution is, preferably but not necessarily, added gradually to the aqueous

solution of the acid (or its equivalent) and the amine of Formula IV (preferably 7-aminocephalosporanic acid). During this addition the pH is preferably, but not necessarily, maintained at about pH 7 by the addition of a base such as alkali metal hydroxide, e.g. sodium hydroxide.

The starting acids having the formula

wherein B is a secondary amino group and X is oxygen or sulfur are prepared by the methods reported in the literature and exemplified below, i.e. from the appropriate secondary amine (B-H) as follows:

Procedure No. 1

To a solution of diethylamine (36.57 g.; 0.5 mole) in 300 ml. absolute ethanol there was added 32.75 g. (0.5 mole) of 85.4% aqueous potassium hydroxide. When the solution had cooled to room temperature there was added to it 38.07 g. (0.5 mole) carbon disulfide. After stirring for 2.5 hours the solvent was removed by distillation in *vacuo* to leave the product, potassium N,N-diethylthiocarbamate as a yellow oil which crystallized on cooling and was used directly in the next reaction by dissolving it in about 150 ml. water and adding thereto with stirring 58.3 g. sodium chloroacetate. The dark green mixture thus produced was heated in a steam bath for one hour. The pH was adjusted to 2 with hydrochloric acid. The product, carboxymethyl N,N-diethylthiocarbamate, separated as an oil which crystallized upon the addition of more water and cooling as tan crystals were collected, recrystallized from hot water and found to weigh 51.5 g. and to melt at 94-96° C. K. A. Jensen, J. Prakt. Chem., 159, 189-192 (1941) reported M.P. 89° C.

Analysis.—Calc'd for $C_7H_{13}NS_2O_2$: C, 40.5; H, 6.32. Found: C, 40.98; 40.82; H, 6.38; 6.40.

Procedure No. 2

Potassium hydroxide (6.55 g., 0.1 mole) was dissolved in 125 ml. absolute ethanol and cooled to 20° C. Carbon disulfide (7.6 g., 0.1 mole) and piperidine (8.5 g., 0.1 mole) were added and the solution was cooled and stirred for thirty minutes. The solvent was removed by distillation in *vacuo* to leave the product potassium N,N-penta-

methylenedithiocarbamate, as a faintly yellow, crystalline solid, 20.4 g., M.P. 228° C.

5 Potassium N,N-pentamethylenedithiocarbamate (9.95 g., 0.05 mole) and sodium chloroacetate (5.8 g., 0.05 mole) were combined in 50 ml. water and heated at 30-35° C. for 1.3 hours. The solution was filtered and cooled. Acidification to pH 2 with hydrochloric acid precipitated crystalline S-carboxymethyl N,N-pentamethylenedithiocarbamate (which is also named 1-piperidinecarbodithioic acid, carboxymethyl ester), which was collected by filtration and found to weigh 8.68 g., M.P. 148-149° C.

10 G. Nachmias, Ann. Chim. (Paris), 7, 584-631 (1952); Chem. Abstr., 45, 7963 and 48, 597 reported M.P. 143° C.

Procedure No. 3

15 To a solution of morpholine (26.1 g., 0.3 mole) in 100 ml. water there was slowly added 22.8 g. (0.3 mole) carbon disulfide and 11.7 g. (0.3 mole) potassium hydroxide. Soon the solution was homogeneous and then 34.2 g. (0.03 mole) sodium chloroacetate was added and the mixture was heated on the steam-bath for thirty minutes. It was necessary to add a few milliliters of 10% sodium hydroxide to keep the pH above 8. The mixture was filtered and acidified to pH 2 with dilute phosphoric acid to precipitate the product, herein called S-carboxymethyl morpholino-dithiocarbamate having the structure given above and also named 4-morpholinecarbodithioic acid, carboxymethyl ester, which was collected, recrystallized from hot isopropyl alcohol and found to weigh 26 g., M.P. 169-170° C.

G. Nachmias, ibid, reported M.P. 162° C.

Procedure No. 4

40 Potassium hydroxide (2.78 g.) was dissolved in 100 ml. water and 6.0 g. benzylmethylamine was added. Carbon disulfide (3.76 g.) was then added while stirring and cooling with ice. When all the oil had disappeared the solid was removed by filtration and 5.6 g. sodium chloroacetate was added and the solution was stored overnight. 45 Acidification precipitated the product, S-carboxymethyl N-methyl-N-benzylthiocarbamate, as an oil which crystallized on scratching (7.9 g.) and was recrystallized from methanol water.

Procedure No. 5

15

Potassium hydroxide (6.55 g.) was dissolved in 100 ml. water and cooled in ice. The icebath was removed and carbon disulfide (6.03 ml.) and N-methylaniline (10.85 ml.) were added. The mixture was stirred for four hours; most of the oil disappeared. Sodium chloroacetate (10.0 g.) was added and the pH was lowered to about 7. The solution was stirred for 40 minutes and then acidified to pH 2 with HCl to precipitate the product, carboxymethyl N-phenyl-N-methyldithiocarbamate, as a crystalline solid which was collected by filtration, 9.4 g., M.P. 200-202° C.d.

Analysis.—Calc'd for $C_{10}H_{11}NO_2S_2$: C, 49.76; H, 4.60; S, 26.58. Found: C, 50.16; H, 4.77; S, 27.05.

Holmberg, J. *Prakt. Chem.* 2, 82, 446; Beilstein, 12, I, 252 reported M.P. 197–198° C.

PROCEDURE NO. 6

Pyrrolidine (10.64 g., 0.15 mole) was dissolved in a solution of 8.25 g. KOH in 100 ml. water and cooled to 0° C. Carbon disulfide (11.4 g., 0.15 mole) was added in 2 ml. portions while stirring in ice; when the additions were complete the pH was slightly alkaline. Sodium chloroacetate (17.5 g., 0.15 mole) was added and the solution was warmed on a hot plate. Stirring was continued for 40 minutes. The solution was acidified with hydrochloric acid and the precipitated product, S-carboxymethyl N,N-tetramethylenedithiocarbamate (also named 1-pyrrolidinecarbodithioic acid, carboxymethyl ester), was collected by filtration and recrystallized from methanol to yield 21.5 g., M.P. 162–163° C.

Analysis.—Calc'd for $C_7H_{11}NS_2O_2$: C, 41.0; H, 5.30; 40 N, 6.84. Found: C, 41.29; H, 5.55; N, 6.80.

Afanas'eva, Chem. Abstr. 54, 20997i reported 141–143° C.

PROCEDURE NO. 7

Diethylamine (14.6 g., 0.2 mole) was dissolved in 150 ml. diethyl ether and carbonyl sulfide was bubbled into the cooled solution until 6.0 g. (0.1 mole) had been added. The solution was stoppered and stored overnight. The solvent was removed at 33° C. to leave as the residue 13.67 g. of diethylammonium N,N-diethylthiocarbamate as an oil which crystallized on cooling and was then dissolved in 75 ml. water. Sodium chloroacetate (7.74 g., 0.066 mole) was added and the solution was stirred at room temperature for 3 hours, heated at 50–55° C. for 50 minutes and then stored overnight at room temperature. The solution was acidified with HCl and extracted with ether. The ethereal extract was washed twice with water and dried over $MgSO_4$. Removal of the solvent by distillation left as the residue 6.5 g. S-carboxymethyl N,N-diethylthiocarbamate as an oil which crystallized on standing in ice and was heated slowly to 50° C. in vacuo (water pump) and then allowed to stand. Melting point 36–38° C. 60 65 70

Analysis.—Calc'd for $C_7H_{13}NO_3S$: C, 43.96; H, 6.85; N, 7.32. Found: C, 44.00; H, 7.01; N, 7.36.

16

10
PROCEDURE NO. 8

10 A solution of 13.1 g. (0.2 mole) potassium hydroxide in 100 ml. water was cooled to 15° and 1-methylpiperazine (20. 0g., 0.2 mole) was added. Carbon disulfide (12.0 ml., 0.2 mole) was then added in 2 ml. portions while maintaining the temperature at about 10° C., taking 15 75 minutes for the additions. The pH was then lowered to 9 with HCl. Sodium chloroacetate (23.2 g., 0.2 mole) was added and the mixture was stirred overnight and then filtered to remove a small amount of a precipitate. The 20 filtrate was evaporated at 38° C. to leave the product, S-carboxymethyl 1-methylpiperazino-dithiocarbamate (also called 1-methyl-4-piperazinecarbodithioic acid, carboxymethyl ester), as a solid residue which was recrystallized from methanether. On standing in water at pH 6 the 25 produce crystallized and was found to have an NMR spectrum consistent with the assigned structure.

In the process for the preparation of the compounds of Formulae (I) and (VII) above, the compounds are sometimes in aqueous solution in the form of their sodium or potassium salt. These compounds in the aqueous phase can then be converted to the free acid, preferably in the cold under a layer of ether by the addition of dilute mineral acid, e.g. 5 N H_2SO_4 to pH 2. The free acid can then be extracted into a water-immiscible, neutral organic solvent such as ether, the extract washed with water quickly in the cold, if desired, and dried, as with anhydrous Na_2SO_4 and the free acid recovered from the ethereal solution. The product in the ethereal extract in its free acid form can then be converted to any desired metal or amine salt, particularly the pharmaceutically acceptable nontoxic amine salts described above, by treatment with the appropriate base, e.g. a free amine such as procaine base or a solution of potassium 2-ethylhexanoate in dry n-butanol. These salts are usually insoluble in solvents such as ether and can be recovered in pure form by simple filtration.

The following examples will serve to illustrate this invention without limiting it thereto. All temperatures are given in degrees centigrade.

50 In the structural formulae given below —ACA— represents the moiety having the formula

Example 1

To a solution of 1.8 g. (0.001 mole) of S-carboxy-65 methyl N,N-dimethylthiocarbamate (Eastman Kodak Co.) and 1.0 g. (0.001 mole) triethylamine in 50 ml. tetrahydrofuran (THF) there was added at 0° C. 1.2 g. (0.001 mole) of isovaleryl chloride. A white precipitate formed which dissolved upon the addition of 2.8 g. (0.001 70 mole) 7-aminocephalosporanic acid (7-ACA) as its triethylammonium salt dissolved in water. The tetrahydrofuran was removed by evaporation under reduced pressure at 35° C. The remaining aqueous mixture was diluted with water and acidified to pH 2 with dilute phosphoric acid and extracted into ethylacetate which was

17

separated and dried over anhydrous $MgSO_4$. After separation of the drying agent there was added to the ethyl acetate solution a solution in dry-n-butanol of sodium 2-ethylhexanoate to precipitate the product (having the formula given above; it may also be named sodium 7-N,N-dimethylthiocarbamoylacetamido - cephalosporanate) which was collected recrystallized three times from wet-n-butanol and found to weigh 2.5 g., M.P. above 210° C. with decomposition.

Analysis.—Calc'd for $C_{15}H_{18}NaN_3O_6S_2$: C, 39.54; H, 3.98; N, 9.23. Found: C, 39.10; H, 3.99; N, 9.16.

This product exhibited Minimum Inhibitory Concentrations (M.I.C.'s) of about 0.5 mcg./ml. versus *S. aureus* Smith, of about 0.8 mcg./ml. versus the benzyl-penicillin-resistant *Staph. aureus* BX-1633-2, of about 0.8 mcg./ml. versus the benzylpenicillin-resistant *Staph. aureus* Russell, of about 0.5 mcg./ml. versus *D. pneumoniae*, of about 0.25 mcg./ml. versus *Str. pyogenes* Digonnet 7 and of about 12.5 mcg./ml. versus *S. enteritidis*.

This product is exceptionally well absorbed upon oral administration.

Example 2

S - carboxymethyl N,N - diethylthiocarbamate (prepared according to Procedure No. 1; 4.14 g.; 0.02 mole) and lutidine (2.02 g.; 0.02 mole) were dissolved in 75 ml. tetrahydrofuran. The solution was cooled and to it was added ethyl chloroformate (2.16 g.; 0.02 mole). The solution was stirred for 20 minutes during which time a salt precipitated out. A solution in aqueous lutidine of 5.22 g. (0.0192 mole) 7-aminocephalosporanic acid was added and stirring continued for 25 minutes. The mixture was diluted with water, acidified and extracted with ethyl acetate. The solid which collected at the interface was removed by filtration. The organic phase was separated, washed with water and freed of solvent by distillation in vacuo to leave the product (as the free acid) as an oil. The oil was dissolved in aqueous base, buffered to neutrality and to this solution there was added N,N'-dibenzyl-ethylenediamine diacetate. The product precipitated (as the amine salt) and was collected by filtration and recrystallized from aqueous dimethylformamide to give 5.5 g., M.P. 172-175° C. with decomposition.

Analysis.—Calc'd for

C, 51.6; H, 5.72. Found: C, 51.25, 51.61; H, 5.75, 5.72.

This amine salt (about 5.0 g.) was suspended in water, acidified with H_3PO_4 and shaken vigorously with ethyl acetate. The ethyl acetate was separated and dried with Na_2SO_4 and after filtering there was added sodium 2-ethylhexanoate. On cooling the sodium salt of this product precipitated and was collected, dried in vacuo over P_2O_5 and found to melt at 195-199° C. with decomposition and to analyze well for the monohydrate.

This sodium salt exhibited Minimum Inhibitory Concentrations (M.I.C.'s) of about 0.25 mcg./ml. versus *S. aureus* Smith, of about 0.8 mcg./ml. versus the benzyl-penicillin-resistant *Staph. aureus* BX-1633-2, of about 0.8 mcg./ml. versus the benzyl-penicillin-resistant *Staph. aureus* 52-75, of about 0.25 mcg./ml. *D. pneumoniae*, and of about 0.125 mcg./ml. versus *Str. pyogenes* Digonnet 7.

70

75

18

Example 3a

To a solution of S-carboxymethyl N,N-pentamethylene-dithiocarbamate (prepared according to Procedure No. 2; 4.38 g.; 0.02 mole) and triethylamine (2.78 ml., 0.020 mole) in 150 ml. tetrahydrofuran cooled in ice there was added 240 g. (0.020 mole; 1.7 ml.) isovaleryl chloride. The mixture was stirred for 20 minutes and then there was added to it a solution in 30 ml. water of 7-aminocephalosporanic acid (5.45 g.; 0.02 mole) and triethylamine (6.54 ml.). Stirring was continued for 40 minutes. The solution was then diluted with water, acidified with H_3PO_4 and extracted with diethyl ether. The ether layer was separated, washed with water and dried over $MgSO_4$. Sodium 2-ethylhexanoate was added to precipitate the sodium salt of the acid having the formula given above, which precipitated and was collected by filtration, 3.8 g., and recrystallized from aqueous butanol and then from aqueous acetone. This sample contained mostly free acid.

Example 3b

S-carboxymethyl N,N-pentamethylene-dithiocarbamate (4.38 g., 0.02 mole) and triethylamine (2.78 ml., 0.02 mole) were dissolved in 120 ml. tetrahydrofuran, the solution was cooled and 1.7 ml. (0.02 mole) isovaleryl chloride was added. The mixture was stirred for 10 minutes. A solution in 30 ml. water of 4.5 ml. triethylamine and 5.45 g. (0.02 mole) 7-aminocephalosporanic acid was added and stirring continued for twenty minutes. The solution containing the product as the triethylamine salt was diluted with water, and extracted with diethyl ether which was discarded. The aqueous solution was then acidified with H_3PO_4 to convert the product to the free acid, which was extracted into ethyl acetate. The organic extract was washed with water and evaporated to leave the product (which may be named 7-N,N-pentamethylene-dithiocarbamoylacetamido-cephalosporanic acid and has the structure given above when sodium is replaced by hydrogen) as an oil which on repeated slurring with ether was converted to 3.2 g. of crystalline product. This acid was converted to its sodium salt in the usual manner by neutralization with sodium 2-ethylhexanoate in dry-n-butanol. The sodium salt having the formula given above was recrystallized from butanol-water and dried in vacuo over P_2O_5 .

To a solution of 3 g. (0.0158 mole) S-carboxymethyl-morpholinylthiocarbamate (prepared according to Pro-

Example 4

19

cedure No. 3) dissolved in 100 ml. tetrahydrofuran there was added 1.6 g. (0.0158 mole) triethylamine and then, at 5° C., 1.9 g. (0.0158 mole) isovaleryl chloride (D.P.I.). The mixture was stirred for 15 minutes and there was then added a solution of 4.3 g. (0.0158 mole) 7-aminocephalosporanic acid dissolved in water by the addition of sufficient triethylamine to dissolve it completely. The resulting clear solution was stirred for 30 minutes and the triethylamine was evaporated off at 30° C. under reduced pressure. The aqueous phase was lowered to pH 2 with dilute phosphoric acid and the product in its acid form was then extracted into ethyl acetate. The ethyl acetate extract was washed with water, dried over MgSO₄ and filtered. To the filtrate there was then added sodium 2-ethylhexanoate which precipitated the product of the formula given above; it was collected, dissolved in a minimum amount of water, reprecipitated by the addition of acetone, collected, recrystallized three times from wet n-butanol and found to weight 4 g.

Analysis.—Calc'd for C₁₇H₂₀NaN₃O₆S₃: C, 41.00; H, 4.03; N, 8.45. Found: C, 41.03; H, 4.03; N, 8.22.

This product exhibited Minimum Inhibitory Concentrations (M.I.C.'s) of about 0.25 mcg./ml. versus *S. aureus* Smith, of about 1.6 mcg./ml. versus the benzylpenicillin-resistant *Staph. aureus* BX-1633-2 of about 1.6 mcg./ml. versus the benzylpenicillin-resistant *Staph. aureus* 52-75, of about 0.25 mcg./ml. versus *D. pneumoniae* and of about 0.25 mcg./ml. versus *Str. pyogenes* Digonnet 7.

Example 5

To 2.4 g. (0.01 mole) of S-carboxymethyl N-phenyl-N-methylthiocarbamate (prepared according to Procedure No. 5) in 100 ml. tetrahydrofuran there was added 1.0 g. (0.01 mole) triethylamine. The solution was cooled to 0° C. in an ice-bath and 1.2 g. (0.01 mole) pivaloyl chloride (trimethylacetyl chloride) was added. The mixture was stirred for ten minutes and there was then added a solution in 100 ml. water of 2.7 g. (0.01 mole) 7-aminocephalosporanic acid and 10 ml. triethylamine. The solution was stirred for 30 minutes and then the organic solvent was evaporated under reduced pressure to leave an aqueous solution of the triethylamine salt of the product which was converted to its acid form by diluting with 20% phosphoric acid and extraction into ethyl acetate. The ethyl acetate extract was dried over anhydrous MgSO₄. Addition thereto of sodium 2-ethylhexanoate in dry n-butanol precipitated 3 g. of the product of the formula given above which was dissolved in wet n-butanol and azeotroped at 40° C. to give a crystalline solid with some oil present. The solid was collected, dissolved in 100 ml. wet butanol and evaporated under reduced pressure to the point where an oil precipitated. Diatomaceous earth ("Celite") was added and the mixture was filtered. Azeotroping of the filtrate was continued to precipitate the product as crystalline rosettes, 200 mgm.

Analysis.—Calc'd for C₂₀H₂₂NaN₃O₆S₃: C, 46.42; H, 3.90; N, 8.12. Found: C, 46.60; H, 4.12; N, 7.85.

This product exhibited Minimum Inhibitory Concentrations (M.I.C.'s) of about 0.125 mcg./ml. versus *S. aureus* Smith, of about 0.4 mcg./ml. versus the benzylpenicillin-resistant *Staph. aureus* BX-1633-2, of about 0.4 mcg./ml. versus the benzylpenicillin-resistant *Staph. aureus* 52-75, of about 0.06-0.125 mcg./ml. versus *D. pneumoniae* and of about 0.062 mcg./ml. versus *Str. pyogenes* Digonnet 7.

Example 6

3,391,141
20

S - carboxymethyl N,N - tetramethylene-dithiocarbamate (prepared according to Procedure No. 6 and also named 1-pyrrolidine-carbodithioic acid, carboxymethyl ester) was used in the process of the above examples to produce the product of the formula given above in 42% yield. Its decomposition point after recrystallization from water-acetone was 160° C.

Analysis.—Calc'd for C₁₈H₂₂NaN₃O₆S₃·3H₂O: C, 39.45; H, 4.68; N, 8.12. Found: C, 39.59; H, 4.45; N, 7.50.

10 Example 7

N - methyl - N - benzylidithiocarbamylacetic acid (2.5 g., 0.01 mole, prepared according to Procedure No. 4 and also named S - carboxymethyl - N - methyl - N - benzylidithiocarbamate) was dissolved in 100 ml. tetrahydrofuran at 5° C. and 1 g. triethylamine was added. The solution was stirred for ten minutes in an ice-bath and 1.2 g. (0.01 mole) isovaleryl chloride (Eastman Kodak Co.) was added. A white precipitate formed immediately. An aqueous solution of 2.7 g. (0.01 mole) 7-aminocephalosporanic acid solubilized by the addition of triethylamine was added all at once to produce a clear solution which was stirred 15 minutes. The tetrahydrofuran was removed by evaporation, 50 ml. water was added and the pH was lowered to 2 with dilute phosphoric acid to convert the product to the acid form which was then extracted into ethyl acetate. The separated ethyl acetate was washed with water, dried over anhydrous MgSO₄ and treated with sodium 2-ethylhexanoate to precipitate 560 mgm. of the product having the formula given above.

Analysis.—Calc'd for C₂₁H₂₂NaN₃O₆S₃: C, 47.45; H, 4.17; N, 7.90. Found: C, 47.93; H, 4.47; N, 7.82.

This product exhibited Minimum Inhibitory Concentrations (M.I.C.'s) of about 0.125-1.0 mcg./ml. versus *S. aureus* Smith, of about 0.4 mcg./ml. versus the benzylpenicillin-resistant *Staph. aureus* BX-1633-2, of about 0.4 mcg./ml. versus the benzylpenicillin-resistant *Staph. aureus* 52-75, and of about 0.5 mcg./ml. versus *Str. pyogenes* Digonnet 7.

Example 8

S - carboxymethyl N,N - dimethylthiocarbamate (4.48 g., 0.025 mole, Eastman Kodak Co.) and 7-aminocephalosporanic acid (6.82 g., 0.025 mole) were combined in 150 ml. water and adjusted to pH 7 with NaOH. The solution was cooled to 4% C. and 25 ml. cold 1 N potassium iodide-iodine solution (i.e. prepared by dissolving 166.01 g. potassium iodide and 253.81 g. iodine q.s. to one liter in water) was added. The pH was kept at about 7 by adding sodium hydroxide. Stirring was continued for about 20 minutes after the last addition of KI-I₂ solution. The reaction mixture was then acidified with H₃PO₄ and shaken with ethyl acetate; the whole mixture was filtered to remove unreacted 7-aminocephalosporanic acid so that the phases could be separated. The separated ethyl acetate phase containing the free acid form of the product was washed with water and the solvent was removed at 35° C. to precipitate 4.3 g. of crystalline product as the free acid. The material was partially dissolved in hot ethyl acetate, filtered and the diethyl ether was added to the filtrate. Storing overnight in the cold precipitated crystals of the product (as the free acid monohydrate) which were collected, washed with a little ether, dried at 56° C. in vacuo over P₂O₅, 425 mgm., M.P. 95-96° C. An analytical sample

21

was recrystallized from acetone-water and dried in vacuo over P_2O_5 .

Analysis.—Calc'd for $C_{15}H_{19}N_3O_7S_2 \cdot \frac{1}{2}H_2O$: C, 42.11; H, 4.71; N, 9.82; S, 14.99. Found: C, 41.74; H, 4.95; N, 9.51; S, 15.57; H_2O , 2.42.

This product exhibited Minimum Inhibitory Concentrations (M.I.C.'s) of about 0.5 mcg./ml. versus *S. aureus* Smith, of about 0.8 mcg./ml. versus the benzylpenicillin-resistant *Staph. aureus* BX-1633-2, of about 0.8 mcg./ml. versus the benzylpenicillin-resistant *Staph. aureus* 52-75, of about 0.5 mcg./ml. versus *D. pneumoniae*, of about 0.25 mcg./ml. versus *Str. pyogenes* Digonnet 7 and of about 3.1 mcg./ml. versus *S. enteritidis*.

Example 9a

7-aminocephalosporanic acid (80% pure, 1.36 g., 0.005 mole) and 3-carboxymethyl *N,N*-diethyl-dithiocarbamate (1.24 g., 0.006 mole, prepared by Procedure No. 1) were dissolved in 100 ml. 2 M pH 7 phosphate buffer maintained at pH 7 by the addition of 10% sodium hydroxide. A 1 N solution of I_2 in 1 N NaI (10 ml.) was added over a 20 minute period with both solutions held at 4° C. After adjusting the pH to 7 with 10% NaOH the solution was stirred for two hours at room temperature. The reaction mixture was filtered to remove a small amount of solid and the filtrate was extracted with ether. The aqueous phase was acidified with 40% H_3PO_4 and the free acid form of the product was extracted into ethyl acetate. The ethyl acetate extract was washed with water and the solvent was removed to leave the product as an oil which was converted by use of sodium 2-ethylhexanoate to the monohydrate of the product of the formula given above. Recrystallization from acetone-dimethylformamide gave 160 mgm., M.P. 152-155° C. with decomposition.

This product exhibited Minimum Inhibitory Concentrations (M.I.C.'s) of about 0.25-0.31 mcg./ml. versus *S. aureus* Smith, of about 0.8 mcg./ml. versus the benzylpenicillin-resistant *Staph. aureus* BX-1633-2, of about 0.8 mcg./ml. versus the benzylpenicillin-resistant *Staph. aureus* 52-75, of about 0.31-0.5 mcg./ml. versus *D. pneumoniae* and of about 0.16-0.25 mcg./ml. versus *Str. pyogenes* Digonnet 7.

This product is exceptionally well absorbed upon oral administration.

Example 9b

7-aminocephalosporanic acid (8.7 g., 0.032 mole) and *S*-carboxymethyl *N,N*-diethyl-dithiocarbamate (7.25 g., 0.035 mole) were combined in 200 ml. pH 7 phosphate buffer (0.2 M), cooled to 8° and adjusted to pH 7 with NaOH; to this mixture there was added 98 ml. of 1 N KI- I_2 solution. The solution was stirred until the pH remained constant; some I_2 was unreacted. The solution was acidified and extracted with ethyl acetate. The organic layer was washed with water and the solvent evaporated to leave the free acid form of the product as an oil. Acetone was added and then sodium 2-ethylhexanoate to precipitate 5.2 g. of the product of the formula given above.

This material was recrystallized successively from acetone-water and butanol-water twice, dried over P_2O_5 and submitted for analysis.

15

Analysis.—Calc'd for $C_{17}H_{22}NaN_3O_7S_2 \cdot H_2O$: C, 41.64; H, 4.93; N, 8.57. Found: C, 41.91; H, 5.21; N, 8.60; H_2O , 4.64.

Example 9c

20

To a cooled solution of *N,N*-diethylcarbamoylactic acid (3.2 g., 0.0167 mole, prepared according to Procedure No. 7) and 1.77 g. (0.0175 mole) triethylamine in 100 ml. tetrahydrofuran there was added 2.12 g. (0.0175 mole) isovaleryl chloride. Stirring was continued for 20 minutes. There was then added a cooled solution of 5 ml. triethylamine and 4.82 g. (0.0167 mole) 7-aminocephalosporanic acid in 50 ml. water and stirring was continued for 25 minutes. The solution was diluted with cold water, acidified with H_3PO_4 and extracted with ethyl acetate. The ethyl acetate extract was washed two times with water, filtered and the solvent evaporated to leave the free acid of the product as an oil which was then dissolved in acetone to which was added a solution of sodium 2-ethylhexanoate in acetone. The product of the formula above precipitated in crystalline form and was collected and recrystallized from water-acetone to yield 2.5 g.

35

Example 10

40

7-aminocephalosporanic acid (6.44 g., 0.024 mole) and *S*-carboxymethyl *N,N*-pentamethylenedithiocarbamate (4.38 g., 0.02 mole, prepared according to Procedure No. 2 and also named 1-piperidine-carbodithioic acid, carboxymethyl ester) were almost completely dissolved in 135 ml. pH 7 0.2 molar phosphate buffer at 0° C. There was then added over 20 minutes 62 ml. 1 N I_2 in 1 N KI solution. The solution was stirred for an additional hour while warming toward room temperature. The solution was filtered and extracted with ethyl acetate. The aqueous phase was separated, acidified with H_3PO_4 and the product in its acid form was extracted into ethyl acetate. The ethyl acetate was separated and washed with water and the ethyl acetate was removed at 33° C. to leave the product as an oil which was diluted with acetone and filtered. The addition of sodium 2-ethylhexanoate precipitated the product as its sodium salt (having the formula given above) as fine crystals which became gummy when collected by filtration. The product was dried in vacuo overnight, found to weigh 3.7 g., recrystallized from aqueous n-butanol and again from a mixture of one part water and one part dioxane to which three parts of acetone were added.

45

Analysis.—Calc'd for $C_{18}H_{22}NaN_3O_7S_2$: C, 45.09; H, 4.63; N, 8.76. Found: C, 45.17; H, 4.94; N, 8.49.

This product exhibited Minimum Inhibitory Concentrations (M.I.C.'s) of about 0.25 mcg./ml. versus *S. aureus* Smith, of about 0.8 mcg./ml. versus the benzylpenicillin-resistant *Staph. aureus* BX-1633-2, of about 0.8 mcg./ml. versus the benzylpenicillin-resistant *Staph. aureus* 52-75, of about 0.25 mcg./ml. versus *D. pneumoniae* and of about 0.25 mcg./ml. versus *Str. pyogenes* Digonnet 7.

50

This product is exceptionally well absorbed upon oral administration.

55

This product is exceptionally well absorbed upon oral administration.

7-aminocephalosporanic acid (6.82 g., 0.025 mole) and S-carboxymethyl N,N-tetramethylenedithiocarbamate (5.13 g., 0.025 mole prepared according to Procedure No. 6 and also named 1-pyrrolidinocarbodithioic acid, carboxymethyl ester) were dissolved in 100 ml. water by adjusting to pH 7 with NaOH. There was then added over 30 minutes 100 ml. of 1 N I₂ in 1 N KI solution while adjusting the pH to 7 after each addition. The solution was then stirred for one hour while adding NaOH to keep the pH at 7. It was then acidified with H₃PO₄ and the product in its acid form was extracted into ethyl acetate, which was separated and washed with water. Evaporation of the solvent left the product as an oil which was dissolved in dioxane; addition thereto of sodium 2-ethylhexanoate in acetone precipitated the product as its sodium salt having the formula given above. The crystals were collected by filtration, washed with acetone, found to weigh 4.3 g., recrystallized from butanol-water and then from water-acetone and dried over P₂O₅.

Analysis.—Calc'd for C₁₇H₂₀NaN₃O₇S₂: C, 43.86; H, 4.33; N, 9.03; S, 13.78; H₂O, none. Found: C, 43.74; H, 4.48; N, 8.93; S, 14.00; H₂O, none.

This product exhibited Minimum Inhibitory Concentrations (M.I.C.'s) of about 0.25 mcg./ml. versus *S. aureus* Smith, of about 0.8 mcg./ml. versus the benzylpenicillin-resistant *Staph. aureus* BX-1633-2, of about 0.8 mcg./ml. versus the benzylpenicillin-resistant *Staph. aureus* 52-75, of about 0.25 mcg./ml. *D. pneumoniae* and of about 0.25 mcg./ml. versus *Str. pyogenes* Digonnet 7.

Example 12

7-aminocephalosporanic acid (5.84 g., 0.02 mole) and S-carboxymethyl N-methyl N-phenyldithiocarbamate (4.82 g., 0.02 mole prepared according to Procedure No. 5) were combined in 225 ml. water and 1 N KI-I₂ solution was added while adjusting to pH 7 as needed with 10% NaOH during the addition. The solution was filtered and acidified with H₃PO₄. The product in its acid form was extracted into ethyl acetate which was separated, washed with water and evaporated to leave the product as an oil which was then taken up in acetone. The addition thereto of sodium 2-ethylhexanoate precipitated the product as its sodium salt having the formula given above, 2.5 g. The product was dissolved in water, filtered, decolorized with carbon, diluted with n-butanol and evaporated at 33° C. until an oil began to form. Diatomaceous earth ("Celite") was added and the solution was filtered. The filtrate was evaporated until it became turbid; the addition of acetone then precipitated the product as fine crystals, 650 mgm. A portion was recrystallized from water-acetone and dried in vacuo over P₂O₅.

Analysis.—Calc'd for C₂₀H₂₀NaN₃O₇S₂: C, 47.90; H, 4.02; N, 8.38; S, 12.79. Found: C, 47.64; H, 4.25; N, 8.22; S, 12.65, 12.45.

This product exhibited Minimum Inhibitory Concentrations (M.I.C.'s) of about 0.25 mcg./ml. versus *S. aureus* Smith, of about 0.4 mcg./ml. versus the benzylpenicillin-resistant *Staph. aureus* BX-1633-2, of about 0.4 mcg./ml. versus the benzylpenicillin-resistant *Staph. aureus* 52-75, of about 0.125 mcg./ml. versus *D. pneumoniae* and of about 0.125 mcg./ml. versus *Str. pyogenes* Digonnet 7.

5 This product is prepared by using in the procedure of Examples 10, 11 or 12 the reagent S-carboxymethyl 1-methylpiperazino-dithiocarbamate prepared according to Procedure No. 8.

10

Example 14

15 7-aminocephalosporanic acid (6.82 g., 0.025 mole) and S-carboxymethyl morpholinodithiocarbamate (5.13 g., 0.023 mole prepared according to Procedure No. 3) were combined in 150 ml. water adjusted to pH 7 with NaOH. The mixture was cooled in ice and 25 ml. of 1 N KI-I₂ solution was added while keeping the pH at about 7 with NaOH. After the addition was complete the solution was stirred for 15 minutes and then acidified with H₃PO₄ and extracted with ethyl acetate. The ethyl acetate was separated and washed with water; removal of the solvent by evaporation left the product in its acid form as an oil which was dissolved in acetone; the addition thereto of sodium 2-ethylhexanoate precipitated the product of the formula given above as 4.5 g. crystals which were recrystallized from water-acetone.

20 This product exhibited Minimum Inhibitory Concentrations (M.I.C.'s) of about 0.5 mcg./ml. versus *S. aureus* Smith, of about 1.6 mcg./ml. versus the benzylpenicillin-resistant *Staph. aureus* BX-1633-2, of about 1.6 mcg./ml. versus the benzylpenicillin-resistant *Staph. aureus* 52-75, of about 0.5 mcg./ml. versus *D. pneumoniae*, of about 0.5 mcg./ml. versus *Str. pyogenes* Digonnet 7 and of about 12.5 mcg./ml. versus *S. enteritidis*.

Example 15

25 This product is prepared by mixing 2 g. nicotinamide and 1 g. of the product of Example 9 in 10 ml. water, saturating the solution with nitrogen and storing it at 56° C. for 19 hours.

50

Example 16

30 Replacement of the diethylamine in Procedure No. 1 with an equimolar weight of the amines having the formula

55

35 60 wherein R¹ and R² have the meanings defined below, respectively, produces the reagents of the formula

40 respectively, which are used to replace on an equimolar basis the S-carboxymethyl N,N-diethyldithiocarbamate used in the procedures of Examples 2 and 9b, respectively, to produce the compounds of the formula

45 75 respectively, wherein X is S when Example 2 is followed

and X is 0 when Example 9b is followed and wherein R^1 and R^2 have the meanings tabulated below:

Example 17

Replacement of the 1-methylpiperazine in Procedure No. 8 with an equimolar weight of

1-ethylpiperazine,
1-n-propylpiperazine,
1-isopropylpiperazine,
1-n-butylpiperazine,
1-sec.-butylpiperazine,
1-tert.-butylpiperazine,
1-isobutylpiperazine,
1-n-amylpiperazine,
1-isoamylpiperazine,
1-n-hexylpiperazine,
1-(3',3'-dimethylbutyl)-piperazine,
1-(2'-hexyl)-piperazine,
1-(3'-hexyl)-piperazine and
1-neopentylpiperazine, respectively,

produces the corresponding S-carboxymethyl 1-(lower)-alkylpiperazinodithiocarbamates (also named as the corresponding 1-(lower)alkyl-4-piperazine-carbodithioic acid carboxymethylesters) which are used to replace on an equimolar basis the S-carboxymethyl N,N-diethyldithio-

carbamate used in the procedures of Examples 2 and 9b, respectively, to produce the compounds of the formula

5

respectively wherein X is S when Example 2 is followed and X is O when Example 9b is followed and wherein R represents ethyl, n-propyl, isopropyl, n-butyl, sec.-butyl, tert.-butyl, isobutyl, n-amyl, isoamyl, n-hexyl, 3',3'-dimethylbutyl, 2'-hexyl, 3'-hexyl and neopentyl, respectively.

Example 18

7-aminocephalosporanic acid (2.7 g., 0.01 mole) and S-carboxymethyl N-methyl-N-benzyldithiocarbamate (2.5 g., 0.01 mole, M.P. 102-103° C., prepared by Procedure No. 4) were combined in 80 ml. water and 25 ml. In I₂-KI was added to the solution after the material had been dissolved by adjusting to pH 7 with NaOH. While the I₂-KI solution was being added the pH was maintained at 7 with 10% NaOH. When the addition was complete and the solution remained at constant pH, the solution was extracted with ethyl acetate and then the aqueous phase was acidified with H₃PO₄, filtered and again extracted with ethyl acetate. The ethyl acetate extract was washed with water and dried over MgSO₄ and to it was added a solution of sodium 2-ethylhexanoate in acetone to precipitate the product of the formula given above. After air drying this material weighed 175 mgm. and was recrystallized from water-n-butanol and dried in vacuo overnight at room temperature and then at 56° C. for two hours. On heating the sample darkened above 153° C. and decomposed at about 203-205° C.

While in the foregoing specification various embodiments of this invention have been set forth in specific detail and elaborated for the purpose of illustration, it will be apparent to those skilled in the art that this invention is susceptible to other embodiments and that many of the details can be varied widely without departing from the basic concept and the spirit and scope of the invention.

We claim:

1. A compound having the formula

wherein

X is oxygen or sulfur;

B represents di(lower)alkylamino wherein the alkyl group may be alike or different, piperidino, methylpiperidino, dimethylpiperidino, pyrrolidino, methylpyrrolidino, dimethylpyrrolidino, morpholino, methylmorpholino, dimethylmorpholino, N'-(lower)alkylpiperazino, N'-(lower)alkyl-methylpiperazino, N'-(lower)alkyl-dimethylpiperazino, trimethyleneimino or hexamethyleneimino.

wherein

n is zero, one, two or three, R is (lower)alkyl and Ar is a radical of the formula

or

wherein

R¹ and R² are each hydrogen, fluoro, chloro, bromo, (lower)alkyl or (lower)alkoxy; A is hydrogen, hydroxyl, (lower)alkanoyloxy, benzoyloxy, a quaternary ammonium radical of the formula

wherein each of W and Z is hydrogen or methyl or, when taken together with M, a monovalent carbon-oxygen bond; and M is hydrogen, a pharmaceutically acceptable nontoxic cation, an anionic charge when A is a quaternary ammonium radical or, when taken together with A, a monovalent carbon-oxygen bond.

2. A compound of claim 1 having the formula

wherein

X is oxygen or sulfur,

M is a pharmaceutically acceptable, nontoxic cation and

B is di(lower)alkylamino wherein the alkyl groups are alike or different, piperidino, methylpiperidino, dimethylpiperidino, pyrrolidino, methylpyrrolidino, dimethylpyrrolidino, morpholino, methylmorpholino, dimethylmorpholino, N'-(lower)alkylpiperazino, N'-(lower)alkyl-methylpiperazino, N'-(lower)alkyl-dimethylpiperazino, trimethyleneimino or hexamethyleneimino.

3. A compound of claim 1 having the formula

wherein

X is oxygen or sulfur,

M is a pharmaceutically acceptable, nontoxic cation, n is zero, one two or three,

R is (lower) alkyl and

Ar is a radical of the formula

29

in which R¹ and R² are each hydrogen, fluoro, chloro, bromo, (lower)alkyl or (lower)alkoxy.

4. A compound of claim 1 having the formula

wherein

X is oxygen or sulfur and M is a pharmaceutically acceptable, nontoxic cation.

5. A compound of claim 1 having the formula

wherein

X is oxygen or sulfur,

n is one, two, three or four and

M is a pharmaceutically acceptable, nontoxic cation.

6. A compound of claim 1 having the formula

wherein

X is oxygen and sulfur and R⁷ and R⁸ each represent hydrogen or methyl.

7. A compound of claim 1 having the formula

wherein

X is oxygen or sulfur, n is one, two, three or four and R⁷ and R⁸ represent hydrogen or methyl.

8. The acid of claim 1 having the formula

and its nontoxic, pharmaceutically acceptable salts.

9. The acid of claim 1 having the formula

3,391,141

30

10. The acid of claim 1 having the formula

and its nontoxic, pharmaceutically acceptable salts.

11. The acid of claim 1 having the formula

and its nontoxic, pharmaceutically acceptable salts.

12. The acid of claim 1 having the formula

and its nontoxic, pharmaceutically acceptable salts.

13. The acid of claim 1 having the formula

and its nontoxic, pharmaceutically acceptable salts.

14. The acid of claim 1 having the formula

and its nontoxic, pharmaceutically acceptable salts.

15. The acid of claim 1 having the formula

and its nontoxic, pharmaceutically acceptable salts.

16. The acid of claim 1 having the formula

and its nontoxic, pharmaceutically acceptable salts.
